(57) **CLAIM**

The ornamental design for a front combination lamp for motor scooter, as shown and described.

DESCRIPTION

FIG. 1 is a perspective view from the front side of a front combination lamp for a motor scooter.

FIG. 2 is a perspective view from the rear side thereof.

FIG. 3 is a perspective view from the front side thereof.

FIG. 4 is a perspective view from the rear side thereof.

FIG. 5 is a front elevation view thereof.

FIG. 6 is a rear elevation view thereof.

FIG. 7 is a left side elevation view thereof.

FIG. 8 is a right side elevation view thereof.

FIG. 9 is a top plan view thereof; and,

FIG. 10 is a bottom plan view thereof.

The portion of the article shown in broken lines is for the purpose of showing environmental structure only and forms no part of the claimed design.
